REGULATABLE FEEDING APPARATUS

Application filed March 29, 1926. Serial No. 98,100.

This invention relates to feeding devices and more particularly to an apparatus capable of feeding material, such as coal, at a regulatable and uniform rate.

5 In order to burn pulverized coal efficiently, it is necessary that the coal be fed to the burner continuously and at a predetermined rate, and that the rate of feed be varied as determined by the load on the boiler. In accordance with the usual practice, the coal is either pulverized initially and then stored in a bin from which it is fed to the furnace, or it is fed directly in a lump or semi-broken form to a pulverizer and from there blown directly 10 into the furnace. If for any reason the fuel feed to the furnace stops, then the flame necessarily goes out and the operation of the furnace is seriously affected. Moreover, the moisture content of coal, as 15 well as other physical characteristics, does not remain uniform, and such variations affect the rate at which the material will feed. It is accordingly desirable that the rate of feed be easily regulatable and that, if the feed 20 is regulated automatically, there should be manually adjustable features which permit one to vary the feed at will, so as to insure a uniform and continuous feeding action.

These considerations apply generally to many 25 materials which are to be fed continuously in measured amount. Also, there is a need for an apparatus which is capable of feeding numerous types of material at regulatable rates.

It is the main object of our invention to 30 provide a simple and efficient feeding apparatus which satisfies these various requirements and which is capable of feeding coal or other material at a regulatable and substantially uniform rate and insuring that the material 35 will be fed continuously and without interruption during normal usage of the apparatus.

It is a further object of our invention to 40 provide a feeding apparatus which may be automatically regulated to give a desired rate 45 of feed but which may be adjusted manually to vary the rate of automatic feed, and which is so constructed and arranged as to require the minimum of attention on the part of the 50 operator.

With these and other objects in view as will be apparent in the following disclosure, our invention resides in the combination of parts set forth in the specification and covered by the claims appended hereto.

55 Referring to the drawings in which like reference numerals indicate like parts:

Fig. 1 is a top plan view of one embodiment of our invention with parts shown in substantially horizontal section;

60 Fig. 2 is a vertical section substantially on the line 2—2 of Fig. 1; and

Fig. 3 is a detail in elevation of the lower portion of the hopper and the adjustable members which determine the amount of fuel feed.

65 In accordance with our invention, we provide a feeding apparatus which comprises a horizontal table rotatable about a vertical axis and a hopper mounted above the table and arranged to present material thereto. A scraper is mounted above the table to sweep material therefrom, and is adjustable to vary the feeding rate. The hopper is preferably located close to the upper surface of the table 70 and provided with an opening in one side into which the scraper projects.

75 As illustrated in the drawings, one embodiment of this invention may comprise a casing 80 which is suitably constructed and arranged relative to other apparatus to which the material is to be fed. A substantially horizontal disk shaped table 12 is rotatably mounted within the casing on a vertical shaft 13 which is suitably supported in bearings 14 and 15 in the casing. The shaft is to be rotated slowly by means of a worm gear 16 suitably fixed thereon and driven by a worm 17 rotated by any suitable power driven mechanism. The top portion 18 of the casing forming a cover has a central opening therethrough communicating with a hopper 20 mounted on the casing. A flange 21 forms the lower half 85 of the hopper and is suitably fastened to and depends from the cover 18 to a position close to the table. The lower portion 21 of the hopper is cut away at 24 to form an opening 90 through the side thereof so that material in the hopper may escape outwardly through this opening and fall over the edge of the 95 100

table. The table as will be observed has a much greater diameter than that of the hopper so as to form an outer, annular portion on which the material may ride in repose after it has escaped through the opening 24.

Since the materials which may be fed by this apparatus vary in their physical characteristics, and their angles of repose will not be the same, we provide a positively actuating mechanism for cutting a certain amount of material from the hopper and scraping it off the annular portion of the table as the latter revolves. This comprises a scraper or knife 25 which is adjustably supported in substantial contact with the top flat surface of the table and projects inwardly through the opening 24. The outer portion of the scraper projects over the edge of the table adjacent the upper end 26 of a chute 20 through which the material is to be fed to other apparatus or to a storage bin.

In the course of our experimentation we have found that the operative surface of this scraper 25 should have a definite angular relation to the direction of travel of the moving material on the rotating table, and that this angular relation should not change as the knife is adjusted into different positions. If the scraper extended radially towards the center of the table, then it would merely serve as an obstruction to the moving material and would not scrape the same from the table. Hence we propose to have this scraper arranged with its operative surface 35 in a non-radial position and preferably at an acute angle to the line of travel of the material, which is indicated by the arrow in Fig. 1, and we propose to move this scraper in such a manner that this angle will remain substantially the same as the position of the scraper is adjusted. Hence, whether a small or a large amount of material is fed, the action of the knife is the same, so that the amount of material fed off the table bears a definite relation to the location of the scraper, and there will be no greater tendency for wet material to pile up against the scraper at one position of adjustment than at another.

50 In order to accomplish this, we prefer to mount the scraper in such a manner that it may be moved always parallel with itself, and its point preferably travels substantially along a radial line toward the axis of the 55 table during adjustment. One simple construction for this purpose comprises, as illustrated, a shaft 30 mounted in the upper portion of the casing in suitable bearings 31 and 32. This shaft is threaded throughout 60 its intermediate portion 34 and an internally threaded nut 35 is mounted on the screw. The nut 35 is made long so that it may be guided easily and it carries depending from it the scraper 25 as clearly illustrated in 65 the drawings. The shaft 30 is arranged to

be rotated suitably such as by means of a hand wheel 36. Stops 37 and 38 are provided on the casing so as to limit the longitudinal movement of the nut which carries the scraper.

As illustrated, the device may be operated by means of a power actuated device, such as a hydraulic motor. This construction comprises a rod 40 slidably mounted in the flanges 41 and 42 projecting from the casing. The rod is adapted to be connected by a collar 43 fixed thereon to a suitable power mechanism capable of reciprocating the rod as desired, which is diagrammatically illustrated as a hydraulic motor 44, arranged to be controlled by a steam pressure regulator or by any other suitable device. This slide rod 40 has an arm 45 pinned thereto and the outer end of this arm has an opening through which the screw threaded shaft 30 passes. This shaft 30 is rotatably fixed to the arm 45 by means of two collars 46 which permit the shaft to rotate but cause it to slide longitudinally with the shaft 40. In order that the shaft 30 may slide, the bearings 31 and 32 are formed merely as stationary concentric sleeves.

If it is desired to move the scraper 25 manually without automatic regulation, the set screw 48 in the flange 42 is screwed into a groove in the rod 40 so as to locate the rod properly and cause it to be held stationary, thereby making it possible to turn the hand wheel 36 and rotate the screw without moving the rod 40. When the rod 40 is held stationary, then the hand wheel 36 is the sole device for moving the scraper 25, but if the automatic features are to be employed, the rod 40 will move the scraper as it is moved by the automatic regulator, and the hand wheel 36 serves solely as an adjustment device adapted to position the scraper 25 adjustably relative to the rod 40, thereby changing its position with reference to the regulating device.

The height of the opening 24 is determined by the angle of repose of the material to be fed, it being necessary that the opening be of such height, or conversely that the table extend to such a distance beyond the hopper, 113 that the material will not fall off the table without the aid of the knife. Also, the opening 24 is of considerable length so as to insure lumps of coal escaping from the opening and not clogging it. The scraper 118 is made in a triangular shape, as illustrated, with its narrow portion projecting into the hopper and much lower than the height of the opening 24. This arrangement is such that if a large lump of coal strikes the point 123 of the scraper it may either be sent out through the opening 24 and off the table or it may ride up over the scraper and come around again for another try, but it is not likely to wedge between the scraper and the 130

flange 21. When the scraper is in its forward position, a portion of the opening 24 is in the rear of the scraper. An adjustable slide is arranged to close this back opening 5 and make it impossible for material to wedge in the rear of the scraper and between it and the hopper flange. This slide 50 is made arcuate in shape, as shown in Fig. 1, so as to fit the outer periphery of the cylindrical flange 21. In order to move the slide to keep the opening in the rear of the scraper 25 closed, we provide a link 52 pivotally connected at one end to the slide 50 and at the other end to the nut 35. These 15 parts are so shaped and arranged that as the scraper 25 moves outwardly, the slide 50 follows along in the rear and as the scraper moves inwardly the slide retreats to make room for it. A cap screw 53 fixed to the hopper projects through a slot 54 in the slide and the head of the screw serves to hold the slide in position against the hopper.

There is a considerable difference between the various materials which may be fed in this device, as well as their behavior under different climatic conditions. If coal is being fed and the apparatus is set so that it will feed, say, 3000 lbs. per hour as indicated by the pointer 55 connected with the nut 35 and moving over the index scale 56, and if the fuel should later become wet due to a rain storm, the coal would tend to pile up more and not feed so fast and the scale would not measure the material correctly. The opening 24 is therefore made adjustable in size so as to compensate for variations in the nature of the material and permit the automatic regulator to control the feeding operation when conditions are normal.

To this end, we provide a gate 58 which is adjustably positioned to vary the size of the opening 24 in the hopper flange. This gate is shaped to fit the outer periphery of the flange 21, as shown particularly in Fig. 1, and the lower front edge of this gate is beveled as shown at 59 in Fig. 3. The gate may be manually adjusted by suitable mechanism, which comprises a shaft 60 rotatably mounted in bearings 61 and 62 and prevented from endwise movement by collars 63 and 64. The shaft 60 is threaded between the bearings 61 and 62 and a screw threaded nut 65 is mounted thereon and connected by a link 66 pivotally connected to the gate 58. A hand wheel 67 serves to rotate the shaft. The gate 58 may be held in position by means of a cap screw 68 projecting outwardly from the hopper flange through a slot 69 in the gate and having an enlarged head which prevents the slide from being pulled away from the flange.

In order to agitate the material in the hopper, we provide an extension 70 threaded on to the end of the shaft 13 above the table 12. A rod 71 passes through the extension

70 and is fixed therein, and two plates 72 are riveted around these parts and suitably connected thereto, so as to form an extensive agitating surface capable of moving the coal around in the hopper as the table 12 revolves. The parts 71 and 72 are shown at right angles to each other in Figs. 1 and 2 for the sake of clearness of illustration.

The operation of this device will now be apparent from the above disclosure. Coal or other material that is to be fed by means of this apparatus is fed into the hopper 20 and is caused to pile up on the table 12 and be revolved by means of the agitating devices and the table. The scraper 25 is suitably adjusted as determined by experience so that it projects within the opening 24 of the hopper flange 21 the desired distance. As the table revolves, the scraper 25 sweeps off the outer layer of material in contact therewith. The remainder of the material above the scraper escapes over the top of the scraper and is held within the hopper by the sleeve 50. If the device is connected through the collar 43 with a steam regulator device or other suitable type of furnace regulator, then the scraper will be moved back and forth parallel with itself, as determined by the load on the boiler and the requirements imposed on the feeding apparatus, and so scrape off the right amount of fuel. By adjusting the hand wheel 36, the blade 25 may be suitably positioned relative to the rod 40, whereby the rate of feed as determined by the power actuated mechanism may be manually varied. By turning the hand wheel 67 on the shaft 60, the gate 58 may be moved back or forth so as to permit a greater or lesser amount of coal to escape through the opening onto the annular portion of the table outside of the hopper so that it may be easily swept from the table when it strikes the scraper.

Having thus described our invention, what we claim as new and desire to secure by Letters Patent, is:

1. A feeding device comprising a rotary table, a hopper disposed above and close to the table and arranged to present material thereto, said hopper having an opening in one side, a scraper having its lower edge disposed substantially in contact with the table and projecting inwardly through said opening to scrape material from the table, the upper edge of said scraper tapering downwardly towards the inner end to form substantially a point adjacent to the surface of the table and being so arranged relative to the opening in the hopper that the coarse lumps of material will not obstruct the opening.

2. A feeding device comprising a rotary table, a hopper thereabove having an opening in one side to present material to the table and permit its escape, a scraper adjustably arranged in said opening over the table to scrape material therefrom, means to move

said scraper back and forth to regulate the amount of feed, and a slide in the rear of the scraper arranged to close the back opening between the scraper and the hopper.

5 3. A feeding device comprising a rotary table, a hopper above the table and arranged to present material thereto, said hopper having an opening in one side, a scraper projecting inwardly through said opening and being 10 so constructed and arranged that it will scrape material from the table through the opening, means to move the scraper back and forth in order to regulate the feed, and a movable gate arranged to vary the opening in advance of the scraper which permits further 15 manual adjustment of the rate of feed.

4. A feeding device comprising a horizontal disk shaped table adapted for rotation about a vertical axis, means to rotate said 20 table, a hopper arranged above the table and close to its upper surface, said hopper being of smaller diameter than the table and having an opening through one side of such height relative to the width of the annular portion of 25 the table outside of the hopper that material in normal repose will be held on the table, and an adjustable scraper having its lower edge close to the table and extending across said annular portion in such a way as to sweep 30 material at a desired rate from the table as the latter rotates.

5. A feeding device comprising a horizontal, flat, disk shaped table, means to rotate the same about a vertical axis, a hopper arranged 35 above and close to the table to present material thereto, said hopper being of smaller diameter than the table and having an opening through one side of such height relative to the width of the annular portion of the 40 table outside of the hopper that material in normal repose will not fall off the table, an adjustable scraper having its lower edge close to the table and extending across said annular portion adjacent the hopper opening 45 at an acute angle to the path of travel of the rotating table, which is arranged to sweep a desired amount of material therefrom as the table rotates, and means to move the scraper parallel with itself to regulate the amount of 50 material fed thereby.

6. A feeding device comprising a hopper for material to be fed, means for feeding the material at a uniform rate from said hopper, 55 a power actuated mechanism for adjusting said feeding means, and a manually operated device for varying the rate of feed corresponding to any given position of the power actuated mechanism.

60 7. A feeding device comprising a rotatable table, means to rotate said table, a hopper arranged above the table to present material thereto, an adjustable member mounted above the table to regulate the rate of flow of the 65 material from said table, and a power ac-

tuated device to move said adjustable member and thereby vary the rate of feed.

8. A feeding device comprising a table adapted for rotation about a vertical axis, means to rotate said table, a hopper arranged 70 above the table to present material thereto, an adjustable scraper mounted above the table to sweep material from said table at a desired rate as the table rotates, and a power actuated device to move the scraper and 75 thereby vary the rate of feed.

9. A feeding device comprising a rotary table, a hopper having an opening in one side arranged to present material to the table, a scraper adjustably mounted to sweep a 80 variable amount of material from the table through said hopper opening, power actuated mechanism to move the scraper and vary the rate of feed, and a manually adjustable device to change the position of the scraper 85 relative to the power actuated mechanism.

10. A feeding device comprising a table rotatable about a vertical axis, means to rotate said table, a hopper arranged above the table to present material thereto, an adjustable 90 scraper mounted adjacent the top surface of the table to sweep material therefrom, a hydraulic motor connected to said scraper to control the position thereof, and manually operable means to vary the relation of said 95 scraper to said hydraulic motor.

11. A feeding device comprising a horizontal disk shaped table rotatable about a vertical axis, a hopper mounted above the table and arranged to present material thereto, a scraper mounted close to the upper surface of the table and having an operative surface in a non-radial position arranged to sweep the material continuously from the table, and means for adjusting the scraper parallel with 100 itself to cause its point to travel along a radial line toward the axis of the table and its operative surface adjacent its point to make the same angle with the direction of travel of the material for any position of adjustment of the scraper.
